UNITED STATES PATENT OFFICE.

GEORGE RILEY LINVILLE, OF FILLMORE, CALIFORNIA, ASSIGNOR OF ONE-THIRD TO
WALTER ERLING COAN AND ONE-THIRD TO JOB VERNON KIMBER, BOTH OF FILL-
MORE, CALIFORNIA.

SAFETY ROLLER-TOOL WRENCH.

Application filed November 23, 1922. Serial No. 602,863.

To all whom it may concern:

Be it known that I, GEORGE RILEY LINVILLE, a citizen of the United States, residing at Fillmore, in the county of Ventura 5 and State of California, have invented certain new and useful Improvements in Safety Roller-Tool Wrenches; and I do hereby declare the following to be a full, clear, and exact description of the invention, such as 10 will enable others skilled in the art to which it appertains to make and use the same.

This invention relates to a wrench designed particularly for use in well drilling by the cable tool method.

15 The invention has for its primary object the provision of a wrench of the nature stated which in service is safe, easy of manipulation and speedy in operation and which has a two-point suspension which prevents the wrench from tipping when the operator applies force and which maintains alinement during the joining of two threaded tools. The two-point suspension also enables a maximum leverage to be 25 brought into play when the tool is in operation.

When in operation, the wrench is suspended from a traveling crane in the derrick house and is designed for holding drill bits, 30 underreamers and analogous tools in vertical position during the operation of attaching or detaching such tools from the box of the drill stem.

Other objects and advantages will be apparent and suggest themselves as the nature 35 of the invention is understood.

While the drawings illustrate an embodiment of the invention it is to be understood that in adapting the same to meet different conditions and requirements, various changes in the form, proportion and minor details of construction may be resorted to without departing from the nature of the invention.

45 Referring to the accompanying drawings forming a part of the application,

Figure 1 is a perspective view of a wrench embodying the invention,

Figure 2 is a front view thereof,

50 Figure 3 is a transverse section on the line 3—3 of Figure 1,

Figure 4 is a top plan view of the swivel wrench jaw,

Figure 5 is a section on the line 5—5 of 55 Figure 4,

Figure 6 is a top plan and a front view, respectively of the retaining plate,

Figure 7 is a top plan view of a supplemental jaw adapted to be detachably connected to the main jaw of the wrench, the 60 dotted lines indicating different sizes whereby the wrench may be adapted for different sizes of work,

Figure 8 is a top plan view of the jaw carrier, and 65

Figure 9 is a sectional detail of portions of the jaw carrier and gate, showing the latch for securing the latter.

Corresponding and like parts are referred to in the following description and designated in the several views of the drawings by like reference characters.

The main frame of the wrench comprises a yoke 1 and a handle 2. The arms of the yoke 1 are provided with eyes 3 to which 75 the lower ends of suspending means 4 are attached, said suspending means preferably consisting of short lengths of chain which are brought together at their upper ends and attached to a hook 5, or analogous device, which may be made fast to a crane (not shown) or other supporting means. It will thus be understood that the wrench has a two-point suspension whereby the same is prevented from tipping sideways and affords better manipulation of the tool, particularly when coupling parts are required to be held in alinement.

A jaw carrier 6 is mounted in the yoke 1 by means of trunnion bolts 7 which are journaled in the outer ends of the arms comprising the yoke and are threaded in the carrier 6. The jaw carrier 6 is of circular form and a portion is cut away to provide an opening which is adapted to be closed by means of a 90 gate 8. The gate 8 is pivoted at one end as indicated at 9 and its free end is half jointed to the opposite end of the carrier 6 as indicated most clearly in Figure 9. A spring actuated latch 10, at the swinging end of 95 the gate 8, is adapted to enter an opening in the end of the carrier 6 and secure the gate when closed against any possible accidental opening. The jaw carrier 6, including the gate 8, is of annular form and is provided 100 upon its top side with a plurality of roller

bearings 11 set in openings formed in the carrier and mounted upon pins.

The jaw 12 is of circular outline and fits snugly within the annular carrier 6 and is formed with an outer flange 13 which underlaps the carrier 6, whereby to limit the upward movement of the jaw with reference thereto. A radial opening 14 extends through an edge of the jaw and is adapted 10 to receive the tool or other part to be held and rotated by means of the wrench. The mouth or entrance of the opening 14 flares to facilitate the application of the wrench to the tool when placing the same in position. 15 Handles 15 extend downwardly and outwardly from the jaw and provide means for rotating the jaw and the tool carried thereby. A retainer 16 is secured to the top side of the jaw 12 and overlaps the jaw carrier 6 and rests upon the roller bearings 11. The retainer 16 consists of a plate which is bolted or otherwise secured to the jaw 12 and which is formed in an edge with an opening 17 to 20 register with the opening 14 of the jaw. It will thus be understood that the jaw 12 is free to rotate within the carrier 6 and the opening 14 thereof is closed by the carrier 6. When the jaw 12 is adjusted to a position to bring the opening 14 thereof in register 25 with the opening in a side of the jaw carrier 6, the tool may be placed in position or removed from the wrench as required. When the tool is placed in position within the opening 14 of the jaw 12, it is held from 30 accidental displacement by closing the gate 8 and fastening the same by means of the latch 10, the tool being rotated by grasping the handle 15 and turning the jaw 12 in the carrier 6, the friction between the jaw and carrier being reduced to the smallest amount 35 possible by means of the roller bearings 11.

The capacity of the wrench is increased by providing supplemental jaws 18 which are

similar in formation to the retainer 16. These supplemental jaws 18 have openings 45 19 of different sizes and by selecting a supplemental jaw of required size and securing the same to the main jaw 12, the wrench may be readily adapted for a tool of special size. For convenience the selected supplemental jaw is placed upon the retainer 16 and secured therewith to the main jaw 12 by the same bolts provided for attaching the retainer to the main jaw.

What is claimed is:

A wrench of the character specified comprising a handle having a yoke at one end, a suspending means secured to each of the arms of said yoke, a jaw carrier journaled to the arms of the yoke and having a portion 60 cut away to provide an ingress and egress opening, a gate for closing said opening pivoted at one end to the carrier and half jointed at its free end to the opposite end of the carrier, a slideable spring pressed latch 65 carried by said gate at its free end and engaging in an opening in the carrier and preventing casual opening of the gate, roller bearings journaled in said carrier and gate and projecting about the upper surfaces 70 thereof, a jaw rotatably mounted in the carrier and having a flange to engage the underside thereof, a retainer secured to the top side of the jaw and overlapping the carriers and resting on the roller bearings and acting jointly with the flange of the jaw to hold the latter in place, and a supplemental 75 jaw having detachable connections with the main jaw whereby to increase the capacity of the wrench.

In testimony whereof I affix my signature in presence of two witnesses.

GEORGE R. LINVILLE.

Witnesses:

JOHN TIMME,
BRUCE H. LOCKARD.
